UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

FARE-BOX.

1,032,843.

Specification of Letters Patent.

Patented July 16, 1912.

Application filed April 14, 1911. Serial No. 621,004.

To all whom it may concern:

Be it known that I, GEORGE B. KOHLER, a citizen of the United States, residing in Philadelphia, Pennsylvania, have invented 5 certain Improvements in Fare-Boxes, of which the following is a specification.

One object of my invention is to improve the construction of a fare box in which a series of compartments are used for the reception of the fares.

A further object is to provide means for raising and lowering the chute so as to allow the chute to be projected into any one of the tills of the fare box, insuring the delivery of all fares into the till in line with the chute.

The invention also relates to certain details of construction which will be fully described hereafter; reference being had to the 20 accompanying drawings in which:—

Figure 1, is a perspective view of my improved fare box; Fig. 2, is a rear view, partly in section; Fig. 3, is a sectional elevation, looking from the front of the box; 25 Fig. 4, is a sectional view on the line *a—a*, Fig. 3; Fig. 5, is a sectional plan view on the line *b—b*, Fig. 3; Fig. 6, is a detached perspective view illustrating one feature of the invention; Fig. 7, is a detached perspective 30 view illustrating another feature of the invention; and Fig. 8, is a view illustrating a detail of the invention.

1 is the body of the fare box, having a fare receiving section 2, in which are inclined deflecting plates 3. At the bottom of the fare receiving section is a movable discharge device 4, of any suitable type. In the present instance, this discharge device consists of a segmental section 5 to which is pivoted a 40 plate 6, which is in turn connected by a link 7. The segmental section is mounted on a shaft 8, on which is an arm 9, connected by a link 10 to an operating lever 11, which is pivotally mounted on the casing and is provided with a handle 12. When it is wished 45 to discharge the fares from the fare receptacle, the handle is moved in the direction of the arrow, Fig. 3; causing the plate 6 to drop away from the bottom of the fare receiving section and discharging the fares into the hopper 13; the segmental section closing the opening in the fare receiving section. I lay no claim to this construction 50 in the present application.

55 In the bottom of the fare box 1 is a drawer

14, in which there is a detachable fare receptacle 15, having a series of removable tills—four in the present instance. Inclosing the fare receptacle is a cover consisting of a series of sliding sections 17, interlocking at the edges, when extended.

18 is a lock on the fare receptacle which engages one of the sections 17, when extended, so as to lock all of the sections in position. On the drawer is a lock 19, which secures the drawer in position in the fare box.

I lay no claim to the above described arrangement of the fare receptacle in this invention.

20 is a chute for directing the fares from the hopper 13 to any one of the tills 16. This chute not only turns on its pivot to aline with any one of the tills, but has also a limited vertical movement. Projecting from the casing are studs 21 and mounted on 70 these studs are arms 22 and 23; there being on the chute pins 24, which extend through openings in the said arms 22 and 23. In order to raise the chute, I extend one of the pins 24 through a slot in the casing 1 of the 80 fare box and mount on the pivot pin an indicating arm 26, provided with a handle 27, so that by raising the handled arm 26 in the slot 25 the chute is lifted; the arms 22 and 23 turning on their pivot studs 21. 85 When the chute is raised, it can be shifted to aline with any one of the tills 16. Indicating marks on the outside of the casing 1, as illustrated in Fig. 1, indicate the particular till with which the chute is in alinement. When the hopper is lowered it enters the mouth of a till, as indicated in Fig. 3, so as to insure the proper delivery of the fares into the till.

On the chute 20 is a weighted arm 28, 95 which tends to normally hold the chute in line with the first till 16, but in order to hold the chute in line with the other tills, I provide a notched segment 29 having notches 30, four in the present instance. Engaging 100 this segment is a tooth 31, carried by an arm 32, pivoted at 33 to the transverse partition 55 within the fare box. The segment between the slots is preferably beveled so as to insure the tooth 31 entering a slot in the 105 chute, when said chute is lowered after adjustment.

Carried by the tooth 31 is a spring bolt 51 which engages the segment when the chute is raised. The bolt is beveled on one 110

side so that, while the chute can be moved from the first till forward, it cannot be returned until the fare receptacle is removed.

The arm 32 has a projection 34 which 5 rests upon the fare receptacle when within the box. As soon as the fare receptacle is removed, a spring bolt 35 forces the arm 32 down and releases the chute from the bolt, after which it can be returned to its 10 first position.

In order to insure the raising of the chute and, at the same time, render positive the discharge of the fares from the fare receiving section into the fare receptacle before 15 the drawer is opened, I provide a shaft 36, on which is a latch lever 37, which is normally located in front of the drawer and prevents its removal. On the inner end of the shaft 36 is an arm 38, held by a latch 20 39, having a long bolt 40, turned down at its rear end 41 in the path of the fare receptacle 15 within the drawer 14. By this construction, when the drawer is open, the latch 39 will hold the lever 37 in the raised position 25 clear of the drawer opening, but, if the drawer is moved to the closed position without the receptacle being in place, the latch 39 will not release the lever 37. If, however, the receptacle is in position, as in Fig. 30 3, and the drawer is closed, then the receptacle comes in contact with the portion 41 of the bolt 40 and will release the lever 37. The lever will be moved to a position in front of the drawer by the weight of the 35 chute, rendering it impossible to open the drawer until the lever is turned by hand. When the hand lever 37 is moved, it lifts the chute 20, so as to permit of the removal of the drawer. This is accomplished by a 40 rod 42 connected to the arm 38 and to an arm 43 pivoted to one of the studs 21. On this arm is a lateral extension 44, Fig. 8, which passes under the arm 22 and, as this arm carries the chute, it will be understood 45 that the chute must be raised before the drawer can be opened.

In order to prevent the accumulation of fares in the fare receiving section, I provide 50 means for discharging the fares from said fare receiving section simultaneously with the raising of the chute, and this is accomplished by pivoting a link 45 to the arm 43. The upper end of this link is slotted, as at 55 46 and on the arm 47, mounted on the shaft 8, is a pin 48, which extends through the slot. As this shaft 8 carries the discharge mechanism, the upward movement of the link 45, on the movement of the hand lever, will 60 shift the discharge mechanism to the open position, and will discharge any fares that may have accumulated in the fare receiving section before the drawer is opened and the fare receptacle removed. By forming a slot 46 in the link 45 the hand lever 12 can be 65 moved without lifting the hopper 20.

This invention is particularly adapted for use on passenger cars of the type in which the conductor is located at a given point on the car and passengers pay their fares as they enter the car. On the first trip of the 70 day the chute is set to align with the No. 1 till, as indicated in the drawings, and when a second conductor takes the car he adjusts the chute by lifting the arm 26, turning it to align with the No. 2 indicating mark, as 75 shown in Fig. 1; bringing the hopper in line with the second till. If another conductor takes the car during the day he shifts the chute before starting his route, the fares being deposited in No. 3 till, and if a fourth 80 conductor has charge of the car he will shift the chute so that all the fares collected by him will be deposited in No. 4 till; thus enabling an accurate record to be kept of the fares collected by each conductor. The 85 conductor can operate the discharge lever 12 as the fares accumulate in the fare receiving section and the fares will be conveyed from the hopper and chute 20 into the proper till. At the end of the day the proper official can 90 unlock the drawer and remove the fare receptacle 15, with the several tills.

Means is provided such, for instance, as the toothed wheel 49, which engages a pin 50 on the upper sliding plate 17 and the 95 several plates are held until the drawer is moved out to its full extent; the upper plate being then engaged by the bolt of the lock 18. When the drawer has been pulled out to its full extent the toothed wheel is released, 100 as the arm 52 on the shaft of the toothed wheel 49 drops back of the fare receptacle 15; allowing the wheel to turn; releasing the pin 50 and permitting the drawer to be removed. This ratchet mechanism 105 forms no part of my present invention. Before the drawer can be opened, the hand lever 37 must be turned so as to clear the drawer and this turning of the hand lever raises the chute 20 clear of the drawer; tilting the discharge device of the fare receiving section; thus insuring the discharge of all the fares from the fare receiving section before the drawer is opened. As soon as the chute is raised and the drawer opened, the 115 chute is released from the control of the tooth 31 and its weight returns it to its first position, so that when the fare receptacle is removed from the drawer and another one placed in its stead and the drawer closed, 120 the chute is in proper position in line with the No. 1 till.

I claim:

1. The combination in a fare box, of a fare receiving section, means for discharging fares from the fare receiving section, a fare receptacle, a chute arranged to direct the fares from the fare receiving section into the fare receptacle, and means for simultaneously moving the chute and for ac- 130

tuating the discharge device of the fare receiving section.

2. The combination in a fare box, of a fare receiving section, a receptacle, a pivoted chute arranged to direct fares from the fare receiving section into the fare receptacle, means for raising and adjusting the chute, said chute having a segment, an arm pivoted to the frame of the fare box, said arm having a tooth engaging the segment and holding it in the position to which it is adjusted.

3. The combination in a fare box, of a fare receiving section, a receptacle, a pivoted chute arranged to direct fares from the fare receiving section into the fare receptacle, means for raising and adjusting the chute, said chute having a segment, an arm pivoted to the frame of the fare box, said arm having a tooth engaging the segment and holding it in the position to which it is adjusted, a latch mounted on the tooth and beveled on one side so as to allow the chute to be moved forward when raised, but preventing it from returning to its first position.

4. The combination in a fare box, of a fare receiving section, a receptacle, a pivoted chute arranged to direct fares from the fare receiving section into the fare receptacle, means for raising and adjusting the chute, said chute having a segment, an arm pivoted to the frame of the fare box, said arm having a tooth engaging the segment and holding it in the position to which it is adjusted, a latch mounted on the tooth and beveled on one side so as to allow the chute to be moved forward when raised, but preventing it from returning to its first position, said pivoted frame having a portion resting on the fare receptacle, when it is in position so that, when the receptacle is removed, the frame will drop, freeing the chute from the control of the tooth and allowing it to return to its first position.

5. The combination in a fare box, of a fare receiving section, a discharge device therefor, a drawer, a fare receptacle in the drawer, a chute arranged to discharge the

fares from the fare receiving section into the fare receptacle in the drawer, a lever normally located in front of the drawer to prevent its removal, and mechanism connecting said lever with the chute and with the discharge mechanism of the fare receiving section so that when the lever is turned the chute is raised and the discharge device of the fare receiving section is actuated before the removal of the drawer.

6. The combination in a fare box, of a fare receiving section, a drawer having a fare receptacle therein, a pivoted chute for directing the fares from the fare receiving section into the fare receptacle, a shaft, a hand lever on the shaft, one arm of the hand lever being normally in position in front of the drawer, an arm on the inner end of the shaft, supporting arms for the chute, a lug connecting the arm on the shaft with one of the supporting arms of the chute so that when the hand lever is turned to release the drawer the chute is raised.

7. The combination in a fare box, of a fare receiving section, a drawer having a fare receptacle therein, a pivoted chute for directing the fares from the fare receiving section into the fare receptacle, a shaft, a hand lever on the shaft, one arm of the hand lever being normally in position in front of the drawer, an arm on the inner end of the shaft, supporting arms for the chute, a lug connecting the arm on the shaft with one of the supporting arms of the chute so that when the hand lever is turned to release the drawer the chute is raised, a latch for engaging the arm on the inner end of the shaft, the bolt of the latch extending to the rear of the drawer compartment and having a portion to be engaged by the fare receptacle when the drawer is closed so as to release the shaft and its operating lever.

In testimony whereof, I have signed my name to this specification, in the presence of two subscribing witnesses.

GEORGE B. KOHLER.
